Pierre Barnes
ATTORNEY

UNITED STATES PATENT OFFICE.

JOHN F. SMITH, OF SEATTLE, WASHINGTON, ASSIGNOR OF FIFTY-FIVE ONE-HUNDREDTHS TO HENRY B. BURKHART, OF SEATTLE, WASHINGTON.

BRAKE-BAND.

1,273,941.

Specification of Letters Patent. Patented July 30, 1918.

Application filed December 20, 1917. Serial No. 208,026.

To all whom it may concern:

Be it known that I, JOHN F. SMITH, a citizen of the United States, residing at Seattle, in the county of King and State of Washington, have invented certain new and useful Improvements in Brake-Bands, of which the following is a specification.

This invention relates to expanding brake bands and especially to that class which are employed to act against the internal surface of an automobile brake drum.

The principal object of the invention is the provision of an efficient brake band of this nature which will be of relatively light weight and constructed to have the parts proportioned to afford ample strength and durability with an economy of material.

A further object is to produce a brake band of this character which will be of simple and relatively inexpensive construction.

The invention consists in a novel form of brake band and in the manner in which the same is produced from an angle bar.

In the accompanying drawings, Figure 1 is a front elevational view of an embodiment of my invention. Figs. 2 and 3 are sectional views through 2-2 and 3-3 of Fig. 1. Fig. 4 is a distended plan view of the band after being cut or formed from a blank or bar, as indicated by broken lines in the view. Fig. 5 is a front elevational view of the distended band shown in Fig. 4.

The blank from which my improved band is constructed is in the nature of an angle bar 10 of steel or wrought iron having rectangularly disposed flanges denoted by 11 and 12 in Figs. 1 and 2. The flange 11, which constitutes the web of the band, when finished is cut away at its ends, as at 13, to afford extremities 14 on the flange 12 which protrude beyond the ends 15 of the latter.

The web flange 11 is, moreover, cut away as shown in Fig. 4, to provide a sinusoidal edge comprising alternating convex and concave portions 16 and 17, respectively. The flange 11 is then punched to provide a hole 18 intermediate its length to accommodate the pivot pin, not shown, by which the completed band is connected to a non-rotatable part of the brake housing, as usual.

The blank, as illustrated in Figs. 4 and 5,

is then heated and subjected to pressure in a suitable forming machine to bend the extremities 14 of the flange 12 against the adjacent ends 15 of the web and the bar formed into a circular shape, as shown in Figs. 1, 2 and 3, of a diameter slightly less than that of the interior of the drum in which it is to be employed.

The band thus produced will have its web 12 narrowest at $x-x$ on the plane 3-3, whence it widens to the maximum widths at the ends 15 and at the hole 18 at the diametrically opposite side of the band, thereby affording a substantially elliptical-shaped opening inclosed by the web.

The advantages of the invention reside in its simplicity, strength with sufficient resiliency to obviate the use of springs, low cost of manufacture and perfect adaptation to the purposes for which intended.

What I claim is—

1. The process of making an expandible brake band from an angle bar, consisting in cutting the web element thereof to be of less length than the flange element and to have a sinusoidal outer edge, punching a hole in the web at its midlength, bending the protruding portions of the flange at substantially right angles and against the respective ends of said flange, and then bending the bar thus formed into a substantially circular shape.

2. The process of making an expandible brake band from a bar having rectangularly disposed flange and web elements, consisting in cutting away the web element at its ends and also along its edge so as to afford relatively narrow portions between the midlength of the bar and each extremity, then bending the bar so that the extremities of the flange will bear against the respective ends of the web, and forming the bar into circular shape with the web directed inwardly and the ends of the bar in proximity to each other.

3. As a new article of manufacture, a brake band consisting of an angle bar formed into a circular shape to provide a web element extending inwardly from one edge of a peripheral flange, the latter having its extremities bent to extend in a direc-

tion radially of the band and against the ends of said web, said web being wider at the aforesaid ends and at the part of the band diametrically opposite thereto, whence
5 the web is tapered to relatively narrow portions at diametrically opposite sides of the band.

Signed at Seattle, Washington, this 12th day of December, 1917:

JOHN F. SMITH.
